UNITED STATES PATENT OFFICE.

THERON H. WILLIAMS AND WILLIAM WRIGHT, OF CHICAGO, ILLINOIS, ASSIGNEES,
BY MESNE ASSIGNMENTS, TO CHICAGO-CLEVELAND CAR ROOFING COMPANY, OF
CHICAGO, ILLINOIS, A CORPORATION OF DELAWARE.

CAR-ROOF CLAMP.

Application filed January 6, 1925. Serial No. 886.

This invention relates in general to improvements in car roof construction, and more particularly to improvements in the all steel rigid type of car roofs for freight cars and the like.

Objects of the invention are the provision of a car roof construction permitting rapid and easy assembly of the roof on freight cars and which when assembled will be water tight and rigidly secured in place; the provision of a construction in which the parts will not become loose as a result of constant vibration or twisting and weaving motions of the car; the provision of a construction in which a wedge clamp may be used so that as the wedge key is positioned it will draw the clamping portions tightly down on the parts, and hold the parts in such clamp tight engagement; the provision of such a roof which may be formed of simple parts easily and inexpensively manufactured and which when assembled will not require frequent repair and replacement, and such other objects and advantages of the invention as may be found to obtain in the structure hereinafter described and claimed.

In the accompanying drawings forming a part of this specification, and showing, for purposes of exemplification, a preferred form and manner in which the invention may be embodied and practiced, but without limiting the claimed invention specifically to such illustrative instance or instances:

Figure 1 is a top plan view of a freight car roof embodying the invention, parts being broken away for clearness in illustration.

Fig. 2 is a side elevational view of the same.

Fig. 3 is a vertical cross-sectional view taken on the line 3—3 of Fig. 1.

Fig. 4 is a cross-sectional view taken substantially on the line 4—4 of Fig. 3, parts being broken away for clearness in illustration.

Fig. 5 is a vertical cross-sectional view taken on the line 5—5 of Fig. 1.

Fig. 6 is a top plan view of one of the clamps in assembled position.

Fig. 7 is a vertical cross-sectional view taken on the line 7—7 of Fig. 1.

Fig. 8 is a perspective view of one of the split tapered wedges.

Referring to the drawings the invention is there shown as embodied in the all steel rigid type of car roofs, having longitudinally extending Z-bar side plates 10 consisting of a vertical web 11, a lower outwardly extending horizontal flange 12 and an upper inwardly extending horizontal flange 13. Extending longitudinally of the car and arranged between the side plates are the usual wooden purlins 14 and ridge pole 15. Extending across the car from side plate to side plate are inverted channel shaped carlines 16, said carlines being arched to conform to the pitch of the roof and consisting of a substantially flat top web 17 connecting a plurality of depending outwardly flaring sides 18 that terminate in outwardly directed lateral flanges 19. At each eaves end the depending sides decrease in height and merge at 21 into the lateral flanges 19 and at such eaves ends the lateral flanges are depressed at 22 and are gradually widened toward the eaves as at 20 to form a seat for the carlines at the side plates, said seat resting upon the upper flange 13 to which it is rigidly secured by rivets 23. The spaces between the side plates and the carlines are closed by intermediate roof sheet sections 24 and end roof sheet sections, said roof sheets extending across the car from side plate to side plate to which they may be rigidly secured by bolts 26 passing through the depending eaves flange 27 of the roof sheets and the vertical web of the side plate. The side edges of the roof sheets are pressed upwardly at 28 to fit over the lateral flanges 19 of the carline so that the main body 29 of the roof sheets may rest upon and be supported by the longitudinally extending purlins and ridge pole when such purlins and ridge pole are used in the roof structure and at each eaves end the portions 28 are gradually widened to fit over the portions 20 of the carlines. The side edges of said roof sheets terminate in inverted channel shaped portions having a substantially

80
85
90
95
100

flat top web 31 connecting the depending outwardly flaring sides 33 whose lower portions terminate adjacent the lower portions of the sides of said carline, said inverted 5 channel shaped portions being shaped similarly to the inverted channel portion of the carlines so that the adjacent sides of adjacent roof sheets are arranged in lapped formation over the inverted channel portion 10 of the adjacent carline to fully enclose and tightly embrace the carline when assembled, as shown in Figs. 4 and 5.

The eaves ends of said side portions of the roof sheets also decrease in height as 15 indicated at 32 and the adjacent depending eaves flanges of adjacent roof sheets are lapped at 33' and such lapped eaves flanges are rigidly held together by bolts 34 that pass therethrough and through the side 20 plates.

In order to secure the inverted channeled side portions of the roof sheets immovably down on the carlines there are provided 25 clamps 35, in the present embodiment illustrated as pressed steel clamps, said clamps consisting of a top web 36 connecting depending outwardly flaring sides 37 that extend down to the lower portions of the sides 30 of the carline and the sides of the inverted channel sides of the roof sheets. The inner faces of the flaring sides 37 of the clamps diverge downwardly somewhat more acutely than the sides of the cooperating carlines, thereby enabling the roof sheets to be 35 securely clamped to the carlines near the general level of the roof.

The top webs of the clamps are pressed upwardly at 38 and each web is apertured as indicated at 39. The web and sides are 40 strengthened by an outwardly extending rib 41 running from the pressed out portion of the web to near the lower edge of the sides of the clamp. The webs of the carlines are apertured to correspond with apertures 42 45 in the webs of the inverted channel sides of the roof sheets.

A depending slotted member or slotted bolt having its upper portion of reduced diameter as indicated at 43 is rigidly secured 50 to the web of the clamp by inserting the reduced portion through the aperture in the web so that the depending member of the bolt is arranged between the sides of the clamp, then riveting the upper end of the 55 bolt down on the outer face of the pressed out portion of the web of the clamp. The opposite end of the bolt terminates in a downwardly tapering portion 65 forming a drift for entering the apertures of the roof sheets and carlines so as to cooperate with 60 said sheets and carline to enforce shifting of the sheets to proper assembled position when the clamp is applied. The lower portion 44 of the bolt is provided with an elongated slot 65 extending from near the portion of

reduced diameter to near the lower end of the bolt. The lower end or face of the slot is curved or inclined in opposite directions as indicated at 46 to facilitate entrance of a 70 wedge 47, said wedge being formed from a strip of metal bent upon itself at 48 to U-shape to form a split wedge. The wedge is tapered toward one end and the greater portion of one longitudinal edge, the upper edge 49, contacts with the bottom face of the web 75 of the carline, as indicated at 51 in Figs. 3 and 7, the remainder of said upper edge 52 of the wedge being downwardly inclined as indicated at 53.

The greater portion of the length of the 80 other longitudinal edge 54, the lower edge, of said wedge is inclined with respect to said upper edge when positioned in the slot of the bolt and the remainder of said edge is inclined upwardly as indicated at 55. The 85 increased taper at one end permits the key to be entered in the slot of the bolt while extending at an angle to the plane of the face of the carline with which the key contacts when in assembled position, thus enabling 90 the key to be readily brought into initial cooperative relation with the slotted bolt and facilitating its driving. The driving of the wedge in the slot draws the clamp down towards the carline so as to cause it to have 95 wedging cooperation with the lower parts of the carline and roof sheets channels, thereby securing the latter by a strong pressure immovably to the carline. After the wedge is in place the free ends 56 are spread transversely as indicated in Fig. 4 to prevent the 100 wedge from creeping or loosening by reason of the constant jarring action of the car and the vertical strains to which it is subjected on the carline.

To support the usual running boards the 105 clamps are provided with angular clips which are riveted thereto, said clips providing a vertical member 58 to which the running board saddles 59 are bolted at 61.

When purlins and ridge pole are utilized in the roof structure, they are secured by 110 bolts 62 positioned in apertures in the top web of the carline and extending down through the channel portion of the carline, said bolts passing through the purlins and ridge pole and secured thereto by nuts 63 threaded against the lower face of the purlins and ridge pole. Said bolts 62 hold the 115 purlins and ridge pole tightly against the lower faces of the lateral flanges 19 of the carline thereby providing adequate support for the main body of the roof sheets between the carlines. In order to clear the 120 rivet heads 63' of the bolts 62 the web of the inverted channel portions of the sides of the roof sheets are provided with registering embossments 64 that fit over and clear such head in lapped formation.

In the present illustrative embodiment of 125

the invention there are shown four wedge clamps secured throughout the length of the carline and such four clamps have been found in practice to be sufficient securing means to rigidly secure the roof sheets immovably down on the carlines without danger of the roof sheets pulling away or tearing loose from the clamps, but of course if it is desired the number of such clamps used 10 may be increased or diminished.

The roof may be applied by first securing the carlines in place, and then laying the sheets down on the carlines so that adjacent sides of the roof sheets embrace the carlines in lapped formation, and the clamps, having the bolt riveted thereto are applied by inserting the bolt through the registering apertures in the web of the carline and the webs of the lapped side portions of the roof sheets, then a tapered wedge is inserted in the slot in each of the clamp bolts and the clamps are thereby drawn down, and after the wedges are fully in place, their free ends are spread. The eaves 25 edges of said roof sheets may be secured to the side plates either before or after the clamps are positioned.

The end roof sheet sections are formed similarly to the intermediate sections except 30 one edge terminates in a depending flange secured to the end fascia or other member at the end of the car.

The invention as hereinabove set forth is embodied in a particular form of construction but may be variously embodied 35 within the scope of the claims hereinafter made.

We claim:

1. A car roof construction involving side 40 plates, carlines extending across the car from side plate to side plate and secured thereto, said carlines having a substantially flat top web and depending outwardly flaring sides, roof sheets extending across the car from side plate to side plate, the sides 45 of the roof sheets terminating in upwardly directed inverted channel portions, said portions consisting of a top web and depending outwardly flaring sides arranged in 50 lapped formation over the top web and depending sides of the carline, and clamps positioned over said upwardly projecting portion of said carlines and the upwardly directed portions of the sides of said roof 55 sheets, said clamps having a top web and depending outwardly flaring sides, the sides of said clamps pressing the sides of said upwardly projecting portion of said roof sheets immovably down on the side of the carlines, the web of said clamps having an 60 aperture therein, a bolt having a portion of reduced diameter, said reduced portion fitting in the aperture in the web of said clamp and the upper end of said reduced portion being riveted down on top of said 65

web, said bolt having a slot therein, and a wedge positioned in said slot, the top edge of said wedge engaging the web of said carline and the bottom edge of said wedge engaging the bottom of said slot. 70

2. A car roof construction comprising, in combination: side plates; carlines extending across the car from side plate to side plate and secured thereto, said carlines having a top web and depending outwardly flaring 75 sides terminating in lateral flanges; roof sheets extending across the car, said roof sheets being secured down on the side plates, the sides of said roof sheets terminating in upwardly directed inverted channel portions 80 having a top web and depending outwardly flaring sides arranged in lapped formation over the top web and sides of said carlines and clamps for holding said lapped sides of the roof sheets down on the carline, said 85 clamps having a top web and depending sides that terminate near the lower portions of the sides of said carline, said clamp having a depending slotted bolt riveted to the top web of said clamp, and a wedge arranged through said slot, one edge of said wedge engaging the bottom face of the top web of the carline and the other edge bearing against the lower edge of said slot, one 90 end of said wedge being spread. 95

3. A car roof construction comprising, in combination: side plates; carlines extending across the car from side plate to side plate; each of said carlines having a top web and depending outwardly flaring sides; roof sheets enclosing the space between said side plates and said carlines; said roof sheets having side flanges, each side flange engaging the side of an adjacent carline and a clamp having a top web and downwardly 100 extending sides engaging over the outside of the web and sides of said carline, for wedging the respective flanges of the roof sheets toward the adjacent sides of said carlines to rigidly clamp said sheets thereto, 105 said clamp having a slotted member depending from the web of the clamp, and a tapered pointed wedge engaging in said slot and engaging the bottom face of the top web of the carline, the narrower end of said wedge 110 being spread. 115

4. A clamp for car roofs comprising a portion providing a web and two depending outwardly flaring sides, said web being pressed upwardly and having an aperture 120 therein, said web and side being strengthened by an outwardly extending rib, a slotted bolt having one end of reduced dimensions, said reduced portion extending in the aperture in the web and riveted down thereon, the lower edge of said slot being inclined in opposite directions and a split wedge extending through said slot, the greater portion of one edge of said wedge 125 engaging the carline with which the clamp 130

- cooperates and the remainder of said edge being inclined with respect thereto, the other edge of said wedge terminating in a line at an angle to the edge engaging the carline.

5. A clamp for car roofs comprising a portion providing a web and a plurality of depending outwardly flaring sides, said web and sides being strengthened by a rib integral therewith terminating short of the lower edges of the sides, a slotted depending member riveted to said web, and a split wedge insertable in said slot, one end of said slotted wedge being bendable after insertion in said slot.

10. A rigid car roof construction involving side plates, carlines extending from side plate to side plate, each of said carlines having a web and depending sides, roof sheets having flanges arranged in lapped formation over the top web of each of the carlines, and clamps for wedging the roof sheets immovably with respect to the sides of the carline, each of said clamps involving a depending slotted member, and a wedge positioned in said slot.

15. A rigid car roof construction involving side plates, carlines extending from side plate to side plate, each of said carlines having a web and depending sides, roof sheets having flanges arranged in lapped formation over the top web of each of the carlines, and clamps for wedging the roof sheets immovably with respect to the sides of the carline, each of said clamps involving a depending slotted member, and a wedge positioned in said slot.

20. A rigid car roof construction involving side plates, carlines extending from side plate to side plate, each of said carlines having a web and depending sides, roof sheets having flanges arranged in lapped formation over the top web of each of the carlines, and clamps for wedging the roof sheets immovably with respect to the sides of the carline, each of said clamps involving a depending slotted member, and a wedge positioned in said slot.

25. A rigid car roof construction involving side plates, carlines extending from side plate to side plate, each of said carlines having a web and depending sides, roof sheets having flanges arranged in lapped formation over the top web of each of the carlines, and clamps for wedging the roof sheets immovably with respect to the sides of the carline, each of said clamps involving a depending slotted member, and a wedge positioned in said slot.

30. A rigid car roof construction involving side plates, carlines extending from side plate to side plate, each of said carlines having a web and depending sides, roof sheets having flanges arranged in lapped formation over the top web of each of the carlines, and clamps for wedging the roof sheets immovably with respect to the sides of the carline, each of said clamps involving a depending slotted member, and a wedge positioned in said slot.

35. A rigid car roof construction involving side plates, carlines extending from side plate to side plate, each of said carlines having a web and depending sides, roof sheets having flanges arranged in lapped formation over the top web of each of the carlines, and clamps for wedging the roof sheets immovably with respect to the sides of the carline, each of said clamps involving a depending slotted member, and a wedge positioned in said slot.

40. A rigid car roof construction involving side plates, carlines extending from side plate to side plate, each of said carlines having a web and depending sides, roof sheets having flanges arranged in lapped formation over the top web of each of the carlines, and clamps for wedging the roof sheets immovably with respect to the sides of the carline, each of said clamps involving a depending slotted member, and a wedge positioned in said slot.

45. A rigid car roof construction involving side plates, carlines extending from side plate to side plate, each of said carlines having a web and depending sides, roof sheets having flanges arranged in lapped formation over the top web of each of the carlines, and clamps for wedging the roof sheets immovably with respect to the sides of the carline, each of said clamps involving a depending slotted member, and a wedge positioned in said slot.

50. A rigid car roof construction involving side plates, carlines extending from side plate to side plate, each of said carlines having a web and depending sides, roof sheets having flanges arranged in lapped formation over the top web of each of the carlines, and clamps for wedging the roof sheets immovably with respect to the sides of the carline, each of said clamps involving a depending slotted member, and a wedge positioned in said slot.

55. A rigid car roof construction involving side plates, carlines extending from side plate to side plate, each of said carlines having a web and depending sides, roof sheets having flanges arranged in lapped formation over the top web of each of the carlines, and clamps for wedging the roof sheets immovably with respect to the sides of the carline, each of said clamps involving a depending slotted member, and a wedge positioned in said slot.

60. A rigid car roof construction involving side plates, carlines extending from side plate to side plate, roof sheets enclosing the space between the side plates and the carlines, the sides of said roof sheets terminating in inverted channel portions and arranged in lapped formation over the carlines, and clamps adapted to embrace the lapped portions of said roof sheets, means for forcing said clamps downwardly to unite the roof sheets immovably to the carlines, involving a depending slotted member carried by the clamp and a wedge arranged in said slot.

65. A rigid car roof construction involving a carline having a top web and depending sides, roof sheets having portions contacting with the carline, and a clamp having a top web and depending sides for securing the roof sheets to the carline, a slotted member carried by said clamp, and a wedge arranged in the slot for forcing the clamp downwardly to unite the roof sheets immovably to the carline, the wedge being arranged longitudinally of the carline and lying wholly within the channel formed by the web and depending sides of the carline.

70. A rigid car roof construction involving a carline having a top web and depending sides, roof sheets having portions contacting with the carline, and a clamp having a top web and depending sides for securing the roof sheets to the carline, a slotted member carried by said clamp, and a wedge arranged in the slot for forcing the clamp downwardly to unite the roof sheets immovably to the carline, the wedge being arranged longitudinally of the carline and lying wholly within the channel formed by the web and depending sides of the carline.

75. A roof clamp for securing roof sheets arranged in overlapped relation to the car lines of railway cars, involving a portion overlying the overlapped parts of the roof sheets and having a pin adapted to pass through registering apertures in the overlapped portions of the sheets and the carline associated therewith, the said pin having a tapering end portion forming a drift for entering said apertures so as to cooperate with said sheets and carline to enforce shifting of said sheets to proper position when the clamp is applied.

80. A roof clamp for securing roof sheets arranged in overlapped relation to the car lines of railway cars, involving a portion overlying the overlapped parts of the roof sheets and having a pin adapted to pass through registering apertures in the overlapped portions of the sheets and the carline associated therewith, the said pin having a tapering end portion forming a drift for entering said apertures so as to cooperate with said sheets and carline to enforce shifting of said sheets to proper position when the clamp is applied.

85. A car roof involving, in combination, a carline, roof sheets, and means for securing adjacent edges of said sheets to the carline, said means comprising a member having a key slot therein extending below the upper face of said carline, and a tapered key adapted to be received by said slot and to have wedging cooperation with an underface of said carline, the taper of said key being increased at one end to permit the key to be introduced into the slot at an angle to its final assembled position.

90. In witness whereof we have hereunto set our hands.

95. THERON H. WILLIAMS.
WILLIAM WRIGHT.
